SAFETY PIN ATTACHMENT

Lew W. Karalus, Bridgeport, Conn.

Application October 26, 1955, Serial No. 542,874

4 Claims. (Cl. 24—156)

The present invention relates to certain new and useful improvements in a conventional-type safety pin having a spring coil at one end and a keeper-equipped guard at the other end and in which the adjacent end of the cooperating openable and closeable end of the pin proper is releasably retained; and the combination therewith of a safe-guarding cover of an ornate character which, generally speaking, takes the form of an elongated elastic strip which has a reverse side against which one side of the safety pin is held flatwise. More specifically, the concept has to do with the safety pin and cover guard in combination with each other and wherein the area of the elastic strip is such that the marginal edges project outwardly beyond the corresponding marginal portions of the safety pin in a manner to conceal the safety pin. More important, the strip is provided on the reverse or inward side and at its opposite ends with outstanding longitudinally spaced elastic pockets. These have mouth portions which open toward each other and the cooperating end portions of the safety pin project into the pockets and are lodged therein and grippingly held and the pocket themselves provide shoulders which are adapted to abut cooperating portions of the garment through which the pin is passed so as to minimize endwise slippage of the thus covered pin.

In carrying out the invention the cover is specifically such in construction that it does not have to be taken off in order to use the pin. The cover is designed so that the pin can be replaced with another and new safety pin in such instances as the point of the pin has become dulled or bent by constant use, this being a feature not found, it is believed, in any ornamental safety pin cover by itself or in conjunction with the safety pin. In fact, only one end of the pin has to be disengaged to facilitate its use. With the cover left on the pin at all times there is added gripping area to enable one to hold the pin more effectively when applying it and bringing it into use. It is also a matter of significance to observe that the cover and pin provide what is in effect a novelly improved "safety pin" possessed of unique style and safety combined.

Although the concept has to do primarily with diaper pinning needs in that it always remains flat, is prevented from sliding endwise and virtually minimizes rotation, it has many other advantages as will be hereinafter set forth.

Other objects of the invention are to provide a safety pin attachment of the aforementioned character which will be comparatively simple in construction, durable, compact, of light weight, highly efficient and reliable in use and which may be manufactured at low cost.

These together with other objects and advantages which will become subsequently apparent reside in the details of construction and operation as more fully hereinafter described and claimed, reference being had to the accompanying drawing forming a part hereof, wherein like numerals refer to like parts throughout, and in which:

Figure 1 is a rear perspective view of a safety pin at-

2

achment constructed in accordance with the present invention;

Figure 2 is a front elevational view, showing the device applied to a safety pin;

5 Figure 3 is a view in horizontal section, taken substantially on the line 3—3 of Figure 2; and

Figure 4 is a perspective view of a modified form of the invention.

Referring now to the drawing in detail, it will be seen 10 that the embodiment of the invention which has been illustrated in Figures 1, 2 and 3 of said drawing comprises a strip 5 of resilient rubber. As illustrated to advantage in Figure 2 of the drawing, the resilient strip 5 has the general outline or shape and dimensions of a conventional safety pin, as indicated at 6.

Formed integrally with the end portions of the resilient strip 5, on one side thereof, is a pair of opposed, inwardly opening pockets 7. The pockets 7 are for the reception of the end portions of the closed safety pin 6.

20 It is thought that the use of the attachment will be readily apparent from a consideration of the foregoing. Briefly, with the safety pin 6 closed, the resilient strip 5 is stretched to engage the pockets 7 over the end portions of said safety pin. Thus, the safety pin is positively pre-

25 vented from accidentally opening by the pocket on the forward end of said pin. When the attachment or cover is in position on the safety pin, the resilient strip 5 is taut or slightly tensioned and the pockets 7 fit the end portions of the pin snugly. The attachment is applied after the

30 safety pin has been inserted and closed. The device may also be placed on safety pins which are not in use to prevent said pins from being opened or swallowed by infants.

In the embodiment of the invention illustrated in 35 Figure 4 of the drawing, reference character 8 designates a resilient rubber strip which tapers from its ends towards its center, said strip having substantially the shape and appearance of a bow tie. Formed integrally with the end portions of the resilient strip 8 on one side or the

40 back thereof and spaced inwardly from the longitudinal edges and the ends of said strip is a pair of spaced, opposed, inwardly opening and substantially flat, resilient pockets 9. The pockets 9 are for the reception of the end portions of a closed safety pin. As will be readily ap-

45 parent, when the ornamental device of Figure 4 of the drawing is applied to a closed safety pin which is in use, the protruding longitudinal marginal side and end portions of the substantially bow tie-shaped strip 8 will overlie and substantially conceal said pin from view.

50 The common or ordinary safety pin 6 in and of itself is highly advantageous in that it is quick and simple to attach and fasten materials. Nevertheless it is very easily opened and this often results accidentally in causing physical injury to babies and adults. Also the pin, as a

55 general thing, is unsightly to all users and many makeshift efforts are followed to camouflage pins. Not only this, it does not stay in one position but shifts from one end to the other causing the two pierced holes to gradually enlarge. Safety pins with guarded heads have been offered but are possessed of the same disadvantages

60 known to users of safety pins.

By way of contrast the ornamentally covered and guarded safety pin herein disclosed will reduce to a minimum the likelihood of the pin opening accidentally.

65 Even if accidentally opened it will remain inside the cover reducing the likelihood of injury to a minimum. With the form of cover seen in Fig. 4 on the safety pin as illustrated in Figs. 2 and 3 instead of having an unsightly safety pin the resultant combination is a decorative pin.

70 With this improvement the pin is always left covered and only the open end of the pin is disengaged. The jacket or cover is left on at all times so that the pin is always

Figure 1 is a rear perspective view of a safety pin at-

stabilized and will always be centered on the material. Because of the elasticity of the cover the pin can be removed and replaced with a fresh or new safety pin whenever the old one has become dull from use. As herein covered there is little or no likelihood of the unwary child swallowing the pin. Because of the jacket construction the back area of the cuff can be used for identification assuring mothers added protection for their children and the cover completely hides the exposed edges of the safety pin. The front side of the pin can be used for any ornamental design, insignia name or emblem. The pin will not rotate as the common safety pin or plastic headed pins will but will remain flat on the material at all times.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. An ornamental safety pin attachment comprising: an elastic strip of an area to substantially cover and shield a safety pin, said strip being tapered from its ends toward its center and having the appearance of a bow tie, and a pair of longitudinally spaced, opposed, inwardly opening and substantially flat, resilient pockets formed integrally on the reverse side of said strip for protective reception and guarded retention of the end portions of the closed safety pin, the longitudinal marginal and end portions of the strip extending beyond the corresponding marginal portions of said pockets, the elasticity of said strip, when applied to said safety pin, serving to retain said end portions in said pockets and thus preventing the safety pin from opening accidentally.

2. As a new product of manufacture, in combination, a conventional-type safety pin having a spring coil at one

end and a keeper-equipped guard at the other end in which the adjacent end of the openable and closable end of the pin proper is releasably retained, and an ornate holder and safeguarding cover for said safety pin comprising a one-piece elongated elastic strip having a flat reverse side against which one side of said safety pin is held flatwise, the area of said strip being such that the marginal edges of the strip project outwardly beyond the corresponding marginal portions of the over-all safety pin and thus serving to conceal the safety pin, said strip being provided on said reverse side and at its opposite end portions with a pair of outstanding coplanar longitudinally spaced elastic pockets having mouth portions opening toward each other and the cooperating end portions of said safety pin projecting into and being lodged and grippingly held in their respective pockets.

3. The structure defined in claim 2 and wherein the mouth portions of the respective pockets are disposed at right angles to the axis of said strip and constitute shoulders projecting laterally from said reverse side, said shoulders being adapted to abut adjacent cooperating portions of the garment through which the pin is passed, whereby to thus minimize endwise slippage of the covered pin.

4. The structure defined in claim 3, and wherein said strip is of predetermined marginal delineation and ornamental appearance.
